UNITED STATES PATENT OFFICE.

WILLIAM R. PATTERSON, OF CHICAGO, ILLINOIS.

MANUFACTURE OF TELEGRAPH-CABLES.

SPECIFICATION forming part of Letters Patent No. 428,055, dated May 13, 1890.

Application filed May 14, 1889. Serial No. 310,751. (No model.)

To all whom it may concern:

Be it known that I, WILLIAM R. PATTERSON, a citizen of the United States, residing at Chicago, in the county of Cook and State of Illinois, have invented a certain new and useful Improvement in the Manufacture of Telegraph-Cables, (Case No. 80,) of which the following is a full, clear, concise, and exact description, reference being had to the accompanying drawing, forming a part of this specification.

My invention relates to the manufacture of electric cables, and its object is to reduce the static capacity of such cables and at the same time provide for readily removing the core or the greater portion thereof whenever such removal from the inclosing-pipe may be desired.

Heretofore cables having the core of insulated conductors protected by a pipe or sheathing of lead have been filled—that is to say, the space or interstices between the pipe and the core have been filled in various ways with various substances and by various processes.

As to the prior state of the art reference is made to United States Letters Patent granted me, as follows: No. 248,209, dated October 11, 1881, for method of filling telegraph-cables with insulating substances; No. 273,592, dated March 6, 1883, for method of filling telegraph-cables with insulating substances; No. 284,226, dated September 4, 1883, for apparatus for filling cables with insulating substances; and No. 378,175, dated February 21, 1888, for telegraph-cable.

My invention herein consists in placing the core of insulated conductors deprived of moisture within the pipe and then forcing insulating-filling into both ends of the pipe. I consider a core consisting of insulated conductors thus deprived of moisture as an unsaturated core as distinguished from such a core which has been dipped in some melted insulating substance—as, for example, hot paraffine—so as to saturate the fibrous insulating-covering of the wires. In connection with this process I use, preferably, a generator of carbon dioxide and a charging-chamber containing the insulating-filling operating upon the general plan of the apparatus described in my said patent of September 4, 1883. This apparatus is, however, so con-

structed as to permit of forcing gas into the cable under a definite pressure and afterward forcing the insulating-filling into the two ends of the pipe under a greater pressure, as would be necessary. The gas within the pipe is thus compressed according to the distance to which the insulating-filling is forced in. The pressure of gas is produced in the usual way by allowing the sulphuric acid to flow into the chamber containing marble-dust or bicarbonate of soda. When the pressure reaches any desired limit, as shown by a gage, the gas is allowed to pass into the cable-pipe. The connection between the gas-reservoir and the cable-pipe is then closed and the other connection between the melted insulated material and the cable-pipe is opened. More gas is then produced in the generator, as before, and the pressure allowed to rise high enough to force the melted insulating material into the ends of the pipe, and thereby still further to compress the gas which had previously been admitted. I therefore preferably provide a cock upon each end of the section of cable which is to be protected, these two cocks being connected with a common pipe leading to the charging-chamber and there branching, each branch containing a cock or valve, and one branch extending down into the insulating-filling and the other branch extending only into the upper portion of the chamber containing the gas. Thus by manipulating the valves and observing a gage the flow of gas and its pressure and the flow of the melted paraffine or other insulating substance may be regulated and controlled.

In the accompanying drawing I have illustrated suitable apparatus for carrying out my method or process, it being understood that I do not limit my patent to any particular apparatus or combination of devices for doing the work.

The coil of pipe *a* may be of any desired length. It is connected at its different ends with the reservoir *b*, containing the melted paraffine and gas under pressure. The cocks *c* *d* are both opened when the coil is being filled. First the gas-cock *e* will be opened and the paraffine-cock *f* closed. The gas is then generated in the generator *g* at such pressure as is required. A pressure from seventy to eighty pounds to the square inch

I have found sufficient. The gas-cock *e* remaining open the coil of pipe *a* will be filled with the gas and the air contained therein under the desired amount of compression. 5 This is accomplished by shutting off the gas-cock *e* and opening the paraffine-cock *f*, and still further increasing the pressure—say up to ninety or one hundred pounds per square inch. The necessary increase of pressure 10 will vary in each individual case, according to the length of the cable which is being filled. The additional pressure necessary to force the paraffine the requisite distance into the ends of the cable which is being filled 15 depends upon the length of said cable, and is therefore necessarily determined independently in each case. In practice I fill the ends to a distance of about twenty-five feet each, regardless of the length of the cable, whether 20 it is two hundred feet long or a thousand. After sufficient paraffine has been forced into the pipe the cocks *c d* are closed and the paraffine allowed to cool. The reservoir *h* is designed for supplying the tank with paraffine. I have 25 shown the core at *i* bared, the lead pipe being cut away for a short distance.

The gas, as is well understood, is generated in the generator *g*, and is conducted therefrom into the reservoir *f* containing the 30 melted paraffine. This tank is not completely filled with paraffine, and hence the gas will rise to the top of the tank, and thus when the paraffine-cock *f* is closed and the gas-cock *e* opened the gas will be forced from the reservoir *f* through the open cock *e* into the pipe *a*, as before described.

The pipe or cable *a*, we will say, is a coil four hundred feet long. The core of insulated wires having been drawn into the pipe, it is 40 desired to fill the space about the core for, say, twenty-five feet at each end of the section. The pipe being of lead is of sufficient strength to stand considerable pressure from within.

45 In order that the static capacity of the cable may be as low as possible, I avoid the use of a liquid or plastic insulating substance in and about the core as far as possible. A filling of some kind to act as a dam to prevent 50 water from running longitudinally in the pipe I have found necessary at the man-holes where cables are laid under ground, since the pipe is so liable to mechanical injury at the man-holes. A short section of filling at the

man-holes I have found, however, sufficient, 55 especially where the core is protected by a lead pipe which has been tested by pneumatic or hydraulic pressure from within. The cable—that is to say, each section *a* of the cable—I therefore fill at each end a short distance 60 with insulating substance, the gas or air, or combination of gases in the pipe being compressed between the insulating-filings at the two ends. The paraffine or other insulating-filling is forced in hot, after which it is allowed 65 to cool before the pressure is removed, so as to hold the gas or air under pressure.

Having thus described my invention, I claim as new and desire to secure by Letters Patent—

70 1. The method of manufacturing electric cables, which consists in forcing insulating-filling into both ends of a section thereof, and thereby compressing the gas or air between said fillings, substantially as described. 75

2. The method of manufacturing telegraph-cables, which consists in drying the core of insulated conductors, drawing the same unsaturated into the pipe, forcing an insulating-filling into the two ends of the pipe, and 80 thereby compressing the gas or air between said fillings, substantially as and for the purpose specified.

3. The method which consists in first drawing the dry unsaturated core into the cable 85 and then forcing an insulating-filling while melted into the ends of the pipe and allowing the insulating-filling thus forced into the ends of the pipe to solidify, thereby holding the atmosphere between the fillings compressed, substantially as described.

4. The method of manufacturing telegraph-cables, which consists in drying the core of insulated conductors, drawing the same unsaturated into the pipe, forcing gas or air 95 into the pipe and then forcing melted insulating-filling into the two ends of the pipe, allowing the insulating-filling to solidify before the pressure is removed, whereby the gas or air is held under pressure, the core being left dry and unsaturated between the fillings, substantially as described.

In witness whereof I hereunto subscribe my name this 11th day of May, A. D. 1889.

WILLIAM R. PATTERSON.
